(57) **CLAIM**

The ornamental design for a mat for hand-building ceramics, as shown and described.

DESCRIPTION

FIG. 1 is a perspective view of a mat for hand-building ceramics;

FIG. 2 is a top view thereof; and,

FIG. 3 is a bottom view thereof.

The broken lines illustrate portions of the mat for hand-building ceramics that form no part of the claimed design.

1 Claim, 3 Drawing Sheets
